(57) **CLAIM**

The ornamental design for a faucet temperature indicator, as shown and described.

DESCRIPTION

FIG. 1 is a top front perspective view of a faucet temperature indicator showing my new design;

FIG. 2 is a side elevational view thereof, the opposite side being a mirror image of the side shown;

FIG. 3 is a top plan view thereof;

FIG. 4 is a bottom plan view thereof;

FIG. 5 is a perspective view showing the faucet temperature indicator attached to a faucet; and,

FIG. 6 is an enlarged view of FIG. 5 thereof.
